UNITED STATES PATENT OFFICE.

PAUL R. SEEMILLER, OF DETROIT, MICHIGAN.

RADIATOR.

Application filed January 21, 1922. Serial No. 530,768.

To all whom it may concern:

Be it known that I, PAUL R. SEEMILLER, a citizen of the United States of America, residing at Detroit, in the county of Wayne and State of Michigan, have invented certain new and useful Improvements in Radiators, of which the following is a specification, reference being had therein to the accompanying drawings.

10 In the manufacture of automobile radiators wherein headers or top and bottom receptacles are connected by tubes, it is the present practice to aperture or punch the bottom wall of the upper header and the top wall of the lower header to receive the ends of the tubes, such aperturing or punching providing out-struck material or flanges that may be soldered or otherwise connected to the walls of the tubes to afford non-leakable 20 connections between the tubes and headers. The out-struck materials or flanges are, in the majority of instances, limited to the size of the apertures and since the tubes are small there is very little material, of sleeve 25 like or lug formation, that may be secured to the tubes. In consequence of this the joints between the tubes and headers are weak, not always perfect, and of such nature as to leak should the radiator receive a blow 30 or be distorted. Repair is not always possible and time and expense are incurred in the maintenance of industrial trucks or vehicles provided with radiators.

35 My invention aims to provide headers which will afford better fastening means and joints for the tubes of a radiator, and reduce, if not completely eliminate, radiator repair.

40 My invention further aims to provide radiator headers with double walls which add rigidity to the radiator core and entire radiator structure.

45 My invention further aims to reinforce the exposed portions of a radiator core, which are liable to receive blows, and thus strengthen and increase the longevity of the radiator.

The improvements will be hereinafter described and then claimed, and reference will now be had to the drawing, wherein:

50 Figure 1 is a vertical longitudinal sectional view of a radiator in accordance with my invention; and

55 Fig. 2 is a plan of a double wall adapted to form part of the radiator header, for instance, the bottom wall of the upper head-

er, the view being taken on the line 2-2 of Fig. 1.

The radiator comprises a lower basin-like header or receptacle 1 which ordinarily has its end edges 2 supported from or by the side frames 3 of an automobile chassis, and this lower header ordinarily has an upper or top wall 4 which has its edges soldered or otherwise connected to the edges of the header to close the basin or receptacle. As mentioned 65 in the beginning, the upper wall 4 of the lower header is apertured or punched, as at 5, to provide outstruck sleeves 6 surrounding the apertures 5 on one face of the wall 4. In the sleeves 6 are placed the lower ends 70 of tubes 7 and the sleeves 6 are connected to the exterior walls of the tubes 7 by solder or other fastening means, generally applied by dipping the lower header in a bath of solder or the like. 75

In addition to the wall 4, I provide another wall 8 which is provided with apertures and sleeves 9 corresponding in number and location to the apertures and sleeves of the wall 4, so that said walls may be placed 80 in parallelism with the sleeves 9 registering with the sleeves 6, so that the sleeves 9 will represent a continuation of the sleeves 6 and afford a greater amount of material to be connected to the tubes 7. The area of the 85 material entering into a joint in the wall 4 of the tubes 7 is practically doubled with the ends of the tubes more firmly braced and anchored so that there cannot be any leak between the walls of the tubes and the walls 90 4 and 8 of the lower header 1.

The wall 8 has marginal portions 10 which engage the marginal portions of the wall 4 and the marginal portions 10 are of greater area than the marginal portions of the wall 4 so that the marginal portions 10 may be indent, as at 11, to overlie the marginal portions of the wall 4. In other words, the marginal portions of the wall 4 are inclosed by the marginal portions of the wall 8 100 with the sleeve portions of the wall 8 in a different plane from the marginal portions 10 of the wall and the walls 4 and 8 will be in spaced relation when the marginal portions thereof are connected or joined, as 105 brought out in Fig. 1. With the marginal portions of the double wall of the header composed of three plies of material, it is obvious that the edges of the double wall are reinforced, that the wall of the header pos- 110

seses a double strength and greater rigidity, and that the additional sleeves 9 permit of the ends of the tubes 7 being positively attached to the lower header 1.

8 The reference numeral 12 denotes an upper header or receptacle which has a bottom composed of walls 13 and 14 provided with alining sleeves 15 and 16 respectively, to receive the upper ends of the tubes 7 and said tubes are secured in engagement with the sleeves 15 and 16 in the manner described in connection with the lower ends of said tubes. The marginal edges of the walls 13 and 14 are also connected similar to the marginal portions of the walls 4 and 8, and the headers 1 and 12 are maintained in spaced relation and connected by frames 17 or other means which will afford a rigid radiator construction.

10 20 The headers 1 and 12 have the usual connections so that a cooling agent, as water, may circulate through the headers and the tubes 7, and said tubes are of cylindrical form having heat radiating or disseminating fins or members 18 thereon. The headers 1 and 12 and the frames 17 may be connected together by any suitable fastening means and is obvious that the headers 1 and 12 may have other shapes than those shown.

15 30 My invention particularly resides in the construction of the tube supporting walls, and while in the drawing, there is illustrated a preferred embodiment of my invention it is to be understood that the construction is susceptible to such changes as fall within the scope of the appended claims.

35 What I claim is:—

1. In a radiator construction wherein top and bottom headers are connected by tubes which establish communication between said headers:—means for connecting said tubes to said headers, said means comprising double walls, each having pressed out sleeves in which the ends of said tubes are secured, said sleeves extending in the same direction. 40 45

2. Means for connecting tubes to radiator heads, as in claim 1, wherein said double walls are in spaced relation and so maintained by the sleeve ends of one wall abutting the other wall. 50

3. As a new article of manufacture, a sheet metal double wall header having alining outstruck tube holding material.

4. A new article of manufacture as in claim 3, wherein the outstruck tube holding material has a sleeve formation projecting into the header. 55

5. In a radiator construction wherein top and bottom headers are connected by tubes which establish communication between said headers:—means for connecting said tubes to said headers, said means comprising spaced parallel sheet metal walls having contacting marginal portions connected together, said walls having outstruck portions extending into said headers and connected to said tubes to maintain said tubes in spaced relation and attached to said walls. 60 65

In testimony whereof I affix my signature in presence of two witnesses.

PAUL R. SEEMILLER.

Witnesses:

GEZA HORVORTII,

KARL H. BUTLER.
